CONNECTING DEVICE

Henry V. D. Schreck, Corning, N. Y., assignor to
 Ingersoll-Rand Company, Jersey City, N. J., a
 corporation of New Jersey

Application April 3, 1935, Serial No. 14,419

1 Claim. (Cl. 74—51)

This invention relates to pumps, compressors or similar apparatus, and more particularly to a connecting device for connecting the pistons of a multi-cylinder machine to the crank shaft.

5 One object of the invention is to prevent each one of a series of pistons connected to the same crank pin from imparting a side thrust to the associated pistons.

Other objects will be in part obvious and in 10 part pointed out hereinafter.

In the drawing accompanying this specification and in which similar reference numerals refer to similar parts,

Figure 1 is a longitudinal sectional elevation 15 of a compressing apparatus equipped with a connecting device constructed in accordance with the practice of the invention, and

Figure 2 is a transverse view taken through Figure 1 on the line 2—2.

20 Referring more particularly to the drawing, 20 designates, in general, a compressing apparatus comprising a bed plate 21 having a hollow extension 22 which supports, in the present instance, a compressing element 23.

25 The compressing element 23, and which may be of the double acting type, comprises a cylinder 24 having a compression chamber 25 to accommodate a piston 26. The ends of the cylinder 24 are provided with the usual heads 27, and at each end of the cylinder are inlet valves 28 to control the admission of fluid medium from an inlet chamber 29 to the compression chamber.

30 Similarly, at each end of the cylinder 24 are discharge valves 30 for controlling communication between the compression chamber 25 and the discharge chamber 31. The chambers 29 and 31 are located in the cylinder 24, as is customary, and each chamber may be provided with a suitable conduit for communicating, in 35 the present instance, the inlet chamber 29 with a source of fluid medium and the chamber 31 with a storage receiver (not shown) or a point of application.

35 The bed plate 21 serves as a support for an engine 32 whereby the compressor piston 26 is driven. The engine 32 is preferably of the four-cycle type and is shown as comprising two cylinders 33 arranged in V-fashion. The cylinders rest upon a distance piece 34 seated upon the bed plate 21 and are suitably bored to provide chambers 35 for the accommodation of pistons 36.

The ends of the chambers 35 are sealed by the usual heads 37 containing sparking plugs 38 to initiate ignition of the fuel whereby the

pistons 36 are actuated. The fuel, employed for this purpose, is conveyed to the chambers by a manifold 39 and its admission into the chambers 35 is controlled by poppet valves 40 of a well known type and which are actuated by a cam shaft 41, as is customary.

5 The cam shaft is preferably disposed in the same vertical plane as a crank shaft 42 supported by the bed plate 21, and a chain 43 trained over sprockets 44 and 45 carried by the cam shaft and the crank shaft, respectively, transmits motion to the former for operating the valves 40.

In accordance with the practice of the invention, the cylinders 33 and 24 are so disposed that their axes all lie in the same plane. The cylinders are, moreover, arranged substantially radially with respect to the crank shaft 42, and the pistons which they contain are so connected that the forces acting against them are substantially directed toward one crank pin, designated herein 46. The means selected for effecting this mode of connection comprises a rod 47 which may be termed a master rod and is connected directly to the crank pin 46 with one end and pivoted with its other end to a cross-head 48 slidable on guideways 49 in the extension 20

therefore, be altogether protected against side thrust. Similarly, any force, such as the resistance of compression, acting against the piston 26 will act exclusively against the crank pin 42, 5 instead of through the connecting devices to the pistons 36.

I claim:

Apparatus of the character described, comprising a plurality of power cylinders and a compressor cylinder having their axes in the same 10 plane, pistons in the cylinders, a crank shaft

having a crank pin, a cross-head interposed between the crank pin and the piston in the compressor cylinder, a rod on the cross-head having a side aperture to receive the crank pin, a closure for the aperture extending into the aperture and having a curved surface to seat against the crank pin, and connecting rods for the remaining pistons pivotally connected to the first mentioned rod adjacent the bearing.
